CLAIM

The ornamental design for a portable folding swivel chair as shown and described.

DESCRIPTION

1.1 : Perspective

1.2 : Front

1.3 : Back

1.4 : Left

1.5 : Right

1.6 : Top

1.7 : Bottom

1.8 : Folded state

1.9 : a first partially assembled configuration

1.10 : a second partially assembled configuration

1.11 : a third partially assembled configuration

The portable folding swivel chair is made of textile, synthetic resin and metal and is used for various outdoor activities, including camping; reproductions 1.1 to 1.7 show the portable chair in an opened state; reproductions 1.8 to 1.11 show the process from a folded state to an unfolded state.
